UNITED STATES PATENT OFFICE.

CHARLES H. KOSTER, OF NEW YORK, N. Y.

LANTERN.

SPECIFICATION forming part of Letters Patent No. 645,320, dated March 13, 1900.

Application filed August 16, 1899. Serial No. 727,401. (No model.)

To all whom it may concern:

Be it known that I, CHARLES H. KOSTER, of the city of New York, borough of Brooklyn, in the county of Kings and State of New York, 5 have invented a new and Improved Lantern, of which the following is a full, clear, and exact description.

My invention relates to an improvement in lanterns, and comprises the novel features 10 hereinafter described and claimed.

Reference is to be had to the accompanying drawing, forming a part of this specification, in which the figure of the drawing is a perspective view of my device.

15 This lantern is of that kind which uses a candle or oil for illuminating purposes. Upon a suitable base B are mounted two concentric rings or bands C and D, the outer band C being of such size as to receive the base of an 20 ordinary lamp-chimney E, and the inner band D being of such size as to receive a candle. This may be split, as shown, so as to be compressed to fit the candle. The base is preferably provided with flanges b at the sides in 25 order to strengthen it. To one side of the base is attached a back piece A, which has flanges a at the sides and is adapted to form a reflector. From the upper end of this back piece a ledge or wind-break F projects for- 30 wardly over the upper end of the lamp-chimney E, which is mounted upon the base. This wind-break lies at a short distance above the lamp-chimney and is also provided with side flanges f, although this feature is not an 35 essential one. The ledge F also prevents rain from reaching the chimney and putting out the light.

Secured to the upper portion of the back are two arms I, formed of wire and extending 40 forwardly, their forward ends being curved in such manner as to embrace the upper portion of the lamp-chimney and hold the same firmly in place. These arms are preferably formed of a single wire, which is bent in a 45 loop, the ends of said wire being passed through holes in the back from the rear and the loop of the wire being soldered to the back. Said arms being resilient readily allow of the chimney being removed for the purpose of lighting the lantern.

50 A bail or handle H is provided consisting of a wire, the ends of which are looped through

holes in the outer ends of the flanges f. For convenience in securing the lantern to a bicycle, carriage, or other vehicle, or to any 55 suitable support, two curved arms or hooks G are secured to the back A and are preferably made of thin sheet metal, so that they may be bent about a bar or made to fit over almost any support. These arms or hooks 60 may be placed either at the top of the back A, as shown in full lines, or at any convenient point below said top, as shown in dotted lines.

Where a lantern is required for temporary purposes only, this device will be found especially useful, as it may be sold cheaply and will answer the purpose of a temporary illumination as well as a more expensive article. The projecting ledge F, which extends over the upper end of the lamp-chimney, forms a 70 sufficient break for the wind to prevent the candle from being blown out.

While I have referred herein to the use of a candle in the lantern, it will be readily understood that the base B may be utilized for 75 the support of a lamp holding oil or other liquid illuminant.

Having thus fully described my invention, I claim as new and desire to secure by Letters Patent—

80 1. A lantern comprising a frame having an integral back and base, the base being provided with means for removably holding a lamp-chimney and an illuminating device, the back acting as a reflector, pliable hooks 85 secured to said back, whereby the lantern may be secured to any convenient object, a support for the upper portion of the lamp-chimney carried by the back, and a shelf extending forwardly from the top of the back 90 and adapted to project over the lamp-chimney to form a wind break or shield, substantially as described.

2. A lantern comprising a frame having a base constructed to removably support an 95 illuminating device and a lamp-chimney, a back extending upward from said base, and a shelf extending forwardly from the top of the back and adapted to project over the top of the lamp-chimney to form a wind break or 100 shield, the said back, base and shelf portions of the frame having flanges at the side edges, substantially as shown and described.

3. A lantern comprising a unitary frame

consisting of a back, a base and a shelf projecting forwardly from the top of the back the base having sockets thereon for receiving a lamp-chimney and a candle, the back serving as a reflector, and the shelf forming a wind break or shield and projecting over the top of the lamp-chimney, and arms projecting forwardly from the front side of the back and adapted to form a support and clamp for the upper portion of the lamp-chimney, substantially as described.

4. A lantern, comprising a base having sockets thereon for receiving a lamp-chimney and a candle, a back secured thereto and acting as a reflector, a shelf projecting forwardly from the back just over the top of the lamp-chimney and adapted to form a wind break or shield, hooks secured to the rear side of said back whereby the lantern may be secured

to any convenient object, and two arms projecting forwardly from the front side of the back and adapted to form a support and clamp for the upper portion of the lamp-chimney, substantially as described.

5. A lantern comprising a frame having an integral back and base, the base having sockets thereon, for removably supporting a lamp-chimney and an illuminating device, the base and back having flanges at the sides and the back acting as a reflector, a shelf projecting forwardly from the back over the top of the lamp-chimney and adapted to form a wind break or shield, and a bail or handle connected with the shelf, substantially as described.

CHARLES H. KOSTER.
